UNITED STATES PATENT OFFICE.

JULIUS ROEDER AND WILHELM WELLMANN, OF WITTEN, GERMANY.

METHOD OF ROLLING TUBES.

Application filed January 11, 1927, Serial No. 160,483, and in Germany January 7, 1926.

Our invention relates to rolling mills and methods used in rolling tubes. More specifically this invention relates to a method for rolling tubes by the so-called Swedish process in which the pierced round is passed through blooming and roughing mills over a mandrel for the purpose of rolling the round into a long hollow bloom. After the usual cutting up into separate pieces has been effected on the same these pieces are reheated and rolled out into finished tubes on the finishing rolls.

Among the objects of our invention may be mentioned—reducing to a minimum the number of passes at the finishing rolls, increasing the production of finished tubes, reducing the wear of the plug and the rod and economizing the heat required during the process.

In order to accomplish these objects, we have combined certain well known types of mills in a novel combination which is illustrated in the accompanying drawing.

The drawing represents a layout in accordance with the invention, comprising blooming, roughing and reducing mills, a saw, a furnace and a finishing mill.

According to the method used at the present time, the pierced round is worked on blooming, roughing and finishing rolls in such a way that in each of the rolls the bloom passes through a definite number of grooves, or passes of decreasing diameter, not only the external diameter of the bloom or tube being diminished, but the wall thickness also being decreased by suitable selection of the roll plugs.

In rolling on a Swedish rolling mill, that is to say, in rolling over a plug and rod, a number of inconveniences are experienced. At the blooming mill and the roughing mill the greatest possible weights are rolled for the purpose of attaining large production. As a result the rolled bloom on the roughing mill obtains a considerable length.

Experience has proved, however, that a very long bloom does not very well admit of being pierced in the plug rolling mill, and furthermore the wear of the plug in the case of long passes is exceedingly great, and it is greater the further the temperature of the bloom falls during the rolling process. Since the mandrel rods are subjected to bending stresses the reduction of the grooves and of the wall thickness from pass to pass must not be too great, because, when there is

a considerable reduction of size in a single pass, the mandrel rod bends too severely and the material that is being rolled is thereby pressed very severely against the walls of the dogs. In this way injuries are caused to the external cylindrical surface of the rolled bloom, and inclined lips at the pierced ends are formed which make it difficult to bring the blooms back smoothly towards the pierced end.

Finally in the event of the passes being too severe the roll plugs are very apt to break. All of these circumstances prevent the bloom from being rolled down at the roughing mill beyond a certain diameter or beyond a certain wall thickness, so that the bloom at the roughing mill after the last pass still has a comparatively large diameter. Now if at the finishing rolls tubes of small diameter and very thin walls are to be formed, an extremely large number of passes must be taken at these rolls because of the large diameter of the tubes coming from the roughing rolls. This has the result, particularly in the case of thin-walled tubes, that the tube becomes cold during the rolling. For the most part the tube is not finished in one heat and must be put back into the re-heating furnace for repeated re-heating, or it does not have the wall thickness intended. As a result large quantities of iron scale are formed. These scalings represent an appreciable loss of iron. Other results of a large number of passes on the finishing rolls are a considerable wearing of the plug, breaking of the plug, and probable damage to the roll pass as well as excessive wear of the mandrel rod.

The present invention removes these defects by interposing between the roughing mill and the finishing mill, a reducing mill upon which the blooms coming from the roughing mill are reduced in their diameter without substantial change of wall thickness. No mandrel is employed in the reducing mill. The bloom thus reduced can be passed through a substantially smaller groove at the finishing mill than an unreduced bloom coming directly from the roughing mill, so that a large number of passes is saved, as compared with the method hitherto employed.

As stated above there is a limit set to the rolling process in the roughing-mill owing to the loss of heat of the bloom and the difficulties arising through such loss during roll-

ing, that is to say it is impossible to proceed 5
rolling the bloom in the Swedish rolling-
mill after the bloom has suffered a definite
loss of heat, without reheating it. The di-
ameter of the bloom, after having passed the
last pass of the roughing-mill, is still much
10 too big in order to be rolled to advantage to
a thin tube on the finishing-mill, that is to
say, by causing said bloom to travel through
a few passes of the latter only. The heat
retained by the bloom after it has travelled
15 through the last pass will be still sufficient to
permit the reduction of its outer or inner di-
ameter respectively without using a man-
drel, whereby the thickness of the wall of
the tube will be increased insignificantly.
20 By reducing-mill a continuously working
rolling-mill is to be understood, consisting
of a certain number of pairs of rollers ar-
ranged one pair behind the other. The
bloom coming from the roughing-mill is
25 passed by means of conveying rollers to the
reducing-mill and passes the rollers of this
apparatus, where it is reduced to a dia-
meter, that will permit the bloom—after it has
been divided into several parts—to be rolled
30 now to a tube of small diameter and very
thin wall, by causing the bloom to travel
through a few passes of said apparatus only.
Thus in contradistinction to the hitherto
customary method, a considerable amount of
35 work has been transferred from the finish-
ing-mill to the reducing-mill. In connec-
tion with this it must be pointed out that
the work in the reducing-mill is done with-
out manual labor, and that while the reduc-
ing-mill is relieving the operator from a por-
tion of his work, the operator will be able to
roll a greater quantity of tubes, since with
40 the new arrangement he is able to employ
much less passes.

Referring more particularly to the draw-
ing, A is a blooming mill of known con-
struction; B is a roughing mill associated
45 therewith; and H is the usual finishing mill.
Between the roughing mill B and the finish-
ing mill H are interposed a reducing mill D,
a saw F, and a reheating furnace G. A
conveyor C facilitates the transfer of the
50 bloom coming off of the roughing mill B to

the reducing mill D. A second conveyor E
leads from the reducing mill to the saw F.

The operation is as follows:—

The pierced ingot, after being rolled out
55 into a bloom in the blooming mill A and
the roughing mill B passes over the conveyor
C into the reducing mill D, and thence over
the conveyor E to the saw F, where the sub-
division of the bloom into separate lengths
60 suitable for treatment in the finishing mill
takes place. From the saw F, the separate
lengths go into the reheating furnace G,
and from there to the individual passes of
the finishing mill H. They thus arrive at
65 the finishing mill with a considerably smaller
diameter than they would have had, had
they come directly from the roughing rolls
according to the methods that have hith-
erto been used. They therefore need consid-
70 erably fewer passes for the purpose of rolling
them into a tube of small diameter and small
wall thickness.

In this way correspondingly less heat is
wasted. No reheating between passes on
the finishing mill is required and a tube of
75 very thin wall is finished while still warm.
Greater reduction in diameter and in wall
thickness can be effected at each pass. For
these reasons wear of the plug and bending
stresses in the rod are normal, and mandrel
so
breakages, together with resulting damage
to the roll passes, ceases. Furthermore owing
to the reduction of roll passes, at the
finishing rolls, the production of finished
tubes is increased very considerably.

We claim:—

A process for rolling tubes comprising
passing the hollow body to be rolled, succes-
sively through a blooming mill over a man-
drel, through a roughing mill over a man-
drel, through a reducing mill, without em-
ploying a mandrel, and through a finishing
mill over a mandrel, the interposition of the
reducing mill between the roughing mill and
the finishing mill serving to reduce the num-
ber of passes required at the finishing mill.

In testimony whereof we have signed our
names to this specification.

JULIUS ROEDER.
WILHELM WELLMANN.
